UNITED STATES PATENT OFFICE.

CHARLES E. WAKEMAN, OF PONTIAC, MICHIGAN.

KNIT MITTEN.

SPECIFICATION forming part of Letters Patent No. 241,458, dated May 10, 1881.

Application filed November 13, 1880. (No model.)

To all whom it may concern:

Be it known that I, CHARLES E. WAKEMAN, of Pontiac, in the county of Oakland and State of Michigan, have invented a new and useful 5 Improvement in Knit Mittens; and I do hereby declare that the following is a full, clear, and exact description of the same.

This invention relates to the manufacture of knit mittens and similar knit articles.

10 The main object of my invention is to effect the widening of the fabric between the wrist and thumb of a mitten in such a way that the rows of stitches of the hand and wrist shall be parallel throughout, and that the rows of 15 stitches of the thumb shall be continuations of rows of stitches of the main fabric. This I accomplish by a stepwise widening, each step representing several rounds. By this method of widening I also am enabled to readily shape 20 the mitten to the hand in a comparatively inexpensive manner, and the gores formed at the junctions of the plies of the fabric at the widened portion are also very strong.

In order that my invention may be clearly 25 understood, I have illustrated in the annexed drawings a knit mitten embodying the same, and will proceed to describe such mitten and the best mode of making it at present known to me.

30 Figure 1 represents the completed knit mitten. Fig. 2 represents a partially-finished mitten ready to have the thumb knit on.

In manufacturing my improved knit mittens on a straight-knitting machine the fabric 35 is begun at the wrist end, and the plies for the wrist portion are knit of uniform width. Then, in order to shape the fabric to the hand on the thumb side, and preferably, also, to some extent on the other side, it is gradually widened 40 in the following manner: An additional needle is picked up on each corner, and the knitting proceeded with for several rounds—say five rounds, more or less—with these additional needles, thus extending the fabric for several

45 rounds with parallel sides, and widening it by two rows of stitches. Again, an additional needle is picked up at each corner, and the fabric again extended parallelly for several rounds. This widens the fabric in most cases 50 sufficiently on the side opposite to the thumb side, but on the thumb side the widening is continued; hence, after the last-mentioned rounds have been knit, an additional needle (one for each ply) is picked up on the thumb 55 side, widening the fabric on this side still

further to the extent of one row of stitches for several rounds. Thus the widening on the thumb side is continued in the stepwise manner set forth until the fabric is knit up to the line *x*, where the thumb is to be joined to it. 60 As many needles as may be deemed expedient are then thrown off on the thumb side, after which the knitting of the fabric may be continued with a uniform width to furnish the required length, and then narrowed to a point 65 in the usual manner. A cut is then made across the fabric on the line *x* by picking out threads across as many rows of stitches as will, together with the rows of stitches already terminating on line *x*, give the number of rows 70 required for the thumb. The loops of the cut thus made, and those on line *x* on both sides of the fabric, are then put on the requisite number of needles and the thumb is knit on, commencing at its base, the rows of stitches in the 75 thumb running parallel to and forming a continuation of those forming the body of the mitten, the line of junction being imperceptible, except on the closest inspection. The mitten may then be completed by separating the plies 80 at the wrist end, and suitably binding or otherwise securing the edge.

It will be observed that the rows of stitches of the thumb are continuations of the parallel rows of stitches of the wrist and hand. 85

In consequence of the hereinbefore-described stepwise widening, the gores at the junctions of the plies at the widening are made very strong, since the weak points are separated by several rounds of knitting, and not in continuous lines, as is the case where widening is effected by picking up needles every half-round. 90

Having thus described my invention, what I claim as new is— 95

1. A knit mitten widened stepwise from the uniform width of the wrist, substantially as before set forth, each widening step consisting of several rounds.

2. A knit mitten in which the rows of 100 stitches of the thumb are continuations of the rows of stitches of the hand and wrist, the hand being widened stepwise from the uniform width of the wrist, substantially as before set forth. 105

In testimony whereof I have signed my name in presence of two subscribing witnesses.

Witnesses: CHARLES E. WAKEMAN.
